UNITED STATES PATENT OFFICE.

WILLIAM J. BEISEL, OF PORT RICHMOND, NEW YORK.

WHEEL-HUB.

1,378,517.

Specification of Letters Patent. Patented May 17, 1921.

Application filed May 20, 1918, Serial No. 235,682. Renewed October 5, 1920. Serial No. 414,828.

To all whom it may concern:

Be it known that I, WILLIAM J. BEISEL, a citizen of the United States, and residing at Port Richmond, Long Island, New York, 5 have invented certain new and useful Improvements in Wheel-Hubs, of which the following is a specification.

This invention relates to wheel hubs, and while it is intended particularly for use in 10 connection with a spring wheel which I have invented and which is set forth in another application filed by me on May 20, 1918, Serial Number 235,681, its use is, of course, not limited to that particular form 15 of wheel. According to this invention, the hub embodies end plates of metal and radially arranged metal plates rigid with the end plates to which the spokes of the wheel are to be fastened. It embodies features of 20 construction which make a very strong and durable hub, and which also facilitates its manufacture. The novel features of the invention will be apparent from the following description, taken in connection with 25 the accompanying drawings.

In the drawings:

Figure 1 is a cross section through a hub embodying my invention;

Fig. 2 is a longitudinal section on the line 30 2—2 of Fig. 1;

Fig. 3 is a perspective view of the metal plates of the hub ready for assembling; and

Fig. 4 is a detail view showing a modified fastening.

35 The hub as shown in the drawings embodies the metal end plates 10 and 11 which are flat and in the form of disks having central openings to receive the metal inner tube 12 which is adapted to receive the spin- 40 dle of the vehicle on which the wheel is used. Connecting the end plates 10 and 11 there are a series of metal plates 13 which radiate from the center of the hub but which do not extend all the way inward to 45 the central openings in the end plate. These radiating plates are provided with lugs 14 projecting through openings 15 in the end plate 10 and lugs 16 extending through the openings 17 in the end plate 11. After the 50 parts are assembled, as shown in Fig. 2, the projections 14 and 16 are upset so as to securely fasten the radial plates to the end plates. The radial plates may be provided with openings 18 to receive fastening means 55 for holding the spokes of the wheel in place.

In Fig. 1 I have shown the inner end of

one metal spoke 22 fitting between the end plates 10 and 11 resting at its inner end on the core 19 and secured to one of the metal plates 13 by the fastening means 23 passing through the openings 18 in plate 13 and corresponding openings in the leaves of the spokes. Where there are no openings through the metal plates 13 as in Figs. 3 and 4, it will be understood that the inner 60 end of the spoke then used may be so shaped as to fit tightly between adjacent plates 13 and the end plates 10 and 11, and will be held in place by the rim of the wheel.

In making the device, the end plate 10 is 70 preferably formed with one-half the total number of radial plates on it and includes those plates which constitute alternate plates around the finished hub. In the same way the end plate 11 is formed with one- 75 half the total number of radial plates secured to it, as is illustrated in Fig. 3. The parts are then brought together, making the projections 14 and 16 pass through the openings 15 and 17 and the parts are then secured together. A cylindrical core 19 of wood is placed between the end plates and around the inner tube 12 before the parts are brought together, and the end plates fit 80 against the ends of this wooden core. The inner edges of the radial plates 13 also rest on the outer surface of this wooden core.

As shown in Fig. 4, the lugs on the ends of plates 13 instead of being secured in place in the openings in the end plates 10 and 11 90 by upsetting the ends may be provided with screw threads 20 adapted to receive the nuts 21 to hold the parts together.

Having thus described my invention what is claimed as new and desired to be secured 95 by Letters Patent is:

1. A wheel hub comprising a wooden core, metal end plates fitting against the ends of said core and radially arranged metal plates rigidly connected to said end plates and extending along and outwardly from said wooden core. 100

2. A wheel hub comprising a wooden core, metal end plates fitting against the ends of said core and radially arranged metal plates 105 rigidly connected to said end plates and extending along and outwardly from said wooden core, and a central metal tube in said wooden core.

3. A metal wheel hub comprising end 110 plates in the form of circular disks with central openings and with radially arranged

openings between said central opening and the margin, and radially arranged flat metal plates between said end plates and having projections on their ends extending into said 5 radial openings in said end plates and upset therein to rigidly hold the parts together.

4. A wheel hub comprising a wooden core, metal end plates fitting against the ends of said core and radially arranged metal plates 10 between said end plates and extending along

and outwardly from said wooden core, the said radial plates being provided with end projections and the end plates being provided with corresponding openings into which said projections extend and in which 15 they are upset to securely hold the parts together.

In testimony whereof I affix my signature.

WILLIAM J. BEISEL.
